(57) **CLAIM**

The ornamental design for a sensor, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front side perspective view of a sensor.

FIG. 2 is a rear side perspective view of the sensor shown in FIG. 1.

FIG. 3 is a front side view of the sensor shown in FIG. 1.

FIG. 4 is a rear side view of the sensor shown in FIG. 1.

FIG. 5 is a right side view of the sensor shown in FIG. 1, the left side of the sensor being identical to or a mirror image of the right side of the sensor.

FIG. 6 is a top view of the sensor shown in FIG. 1.

FIG. 7 is a bottom view of the sensor shown in FIG. 1.

The attached Appendix includes reference views relating to the present design. The color shown in the figures in the Appendix forms no part of the claimed design.

FIG. 8 is a front side perspective view of the sensor of FIG. 1 shown in color.

FIG. 9 is a front side view of the sensor of FIG. 1 shown in color.

FIG. 10 is a right side view of the sensor of FIG. 1 shown in color, the left side of the sensor being identical to or a mirror image of the right side of the sensor.

FIG. 11 is a rear side perspective view of the sensor of FIG. 1 shown in color.

FIG. 12 is a rear side view of the sensor of FIG. 1 shown in color.

FIG. 13 is a top view of the sensor of FIG. 1 shown in color; and,

FIG. 14 is a bottom view of the sensor of FIG. 1 shown in color.
